UNITED STATES PATENT OFFICE.

WALLACE D. JOHNSON, OF BELOIT, WISCONSIN, ASSIGNOR TO YATES-AMERICAN MACHINE COMPANY, OF BELOIT, WISCONSIN, A CORPORATION OF DELAWARE.

BAR-AFTER-CUT QUICK RELEASE.

Application filed March 21, 1927. Serial No. 177,025.

The present invention relates to wood-working machines, and has to do particularly with the way in which the bars-after-cut associated with the top heads in such 5 machines are withdrawn from and adjusted as to working position.

The principal object of the invention is to provide an improved release by means of which a bar-after-cut may be quickly withdrawn 10 from working position.

Another important object is to provide an improved adjuster by means of which a bar-after-cut equipped with the previously mentioned release may be adjusted as to 15 working position, and, when once adjusted, will be returned accurately to such position after operation of the release.

While the foregoing statements are indicative in a general way of the nature of the 20 invention, other objects and advantages will be evident to those skilled in the art upon a full understanding of the construction, mounting and adjustment of the bar-after-cut.

One embodiment of the invention is presented herein for the purpose of exemplification, but it will of course be appreciated that the invention is susceptible of embodiment in other structurally different forms coming 30 equally within the scope of the appended claims.

In the accompanying drawings:

Fig. 1 is an end view of a top head yoke, showing in association therewith a bar-after-cut equipped with the quick release and adjustment features of the invention;

Fig. 2 is a rear view of one end of the yoke and bar; and

Fig. 3 is a transverse section through the 40 yoke and bar, taken on the line 3—3 of Fig. 2.

The bar-after-cut 10 is positioned beneath the upper portion 11 of a cutter head yoke 12, and is provided at its ends with lugs 13 which extend into inclined grooves 14 in the side portions 15 of the yoke, whereby to permit the bar to be shifted toward or away from the upper portion of the yoke along an inclined plane.

A face plate 16 is secured to the bottom of the bar by means of a number of screws 17, and the front edge of the plate is beveled off in order to fit closely up to the cutting circle 19 of the associated cutter head. The rear edge 20 of the plate is beveled off like

the front edge in order to permit the plate to be reversed in position upon becoming worn. Inasmuch as the screws 17 are nearer one edge of the plate than the other, extra threaded apertures 21 are provided in 60 the plate to receive the screws when the plate is reversed.

The bar 10 backs up against a shaft 22 which extends through the upper portion of the yoke from one side portion of the same 65 to the other. The shaft is eccentrically journaled at its ends in apertures 23 formed in the side portions of the yoke, and is supported intermediate its ends by concave plates 24 which bear against journaling portions 25 on the shaft and are adjustable 70 toward or away from such portions by means of set screws 26 mounted in the yoke. The bar is held against the eccentric surface of the shaft by means of two springs 27 which 75 are positioned in the grooves 14 between the lugs 13 and two blocks 28 in the lower ends of the groove. The pressure with which the bar is held against the shaft may be increased or diminished by moving the blocks 80 farther into or out of the grooves. In order to permit the blocks to be moved conveniently, the bottoms 29 of the same are formed at an angle to the sides of the grooves and screws 30 are extended through the slots 85 31 in the tapering corners of the blocks into the yoke. When the screws are turned up, the blocks will be cammed upwardly in the grooves by the heads of the screws, and, when the screws are turned in the opposite 90 direction, the blocks will move downwardly under the action of the springs 27.

The working position of the bar 10 relative to the cutting plane of the cutter head may be varied by turning the eccentric shaft 95 slightly in one direction or the other, such turning movement being effected by a worm 32 which is in mesh with a pinion 33 secured to one end of the eccentric shaft. The worm is secured to the lower end of a shaft 34, 100 and a control handle 35 is secured to the upper end of the shaft for turning the same. The pinion, worm and shaft are encased within a housing 36 which is pivoted to the yoke about an axis concentric with that of 105 the eccentric shaft. As a result, when the handle is gripped and the housing is swung about its pivotal axis, the worm locks the pinion to the housing and the eccentric shaft is turned through a corresponding arc, caus- 110

ing the eccentric face of the shaft in contact with the bar to be retracted. The bar will of course follow such eccentric face under the action of the springs 27 and will be withdrawn from working position. When the housing is swung in the opposite direction again, the bar will be returned to precisely the same working position as that to which it had previously been adjusted by the worm.

10 The handle 35 is prevented from being turned inadvertently while it is being swung, by means of a small spring 37 which is attached to the housing and bears frictionally against a serrated surface on the handle,

15 and the housing 36, which forms the support for the handle, is locked in working position by means of a spring-pressed pin 38 which is carried by the casing and is provided with a finger knob 39. The pin ex-

20 tends into an aperture 40 in one end of an arcuate arm 41 secured to the yoke, and, when the pin is withdrawn from the aperture and the handle is swung downwardly, the end of the pin will slide freely along

25 the smooth surface of the arm. A stop lug 42 is provided on the arm a substantial distance from the aperture 40 for limiting the extent to which the handle and housing may be swung.

30 The front edge of the upper portion 11 of the yoke is sharply beveled to provide a snug sliding fit with the opposed face of the bar 10, and such fit effectively prevents chips from entering and wedging between the yoke

35 and the bar.

From the foregoing description, it will be appreciated that a bar-after-cut embodying the features of this invention may be accurately adjusted as to working position by 40 turning a single control handle in one direction or the other, and may be released temporarily from such working position by swinging the same handle, without disturbing the adjustment of the working position.

45 I claim:

1. In a wood-working machine, a cutter head, a bar-after-cut, and means movable in one direction to adjust the working position of the bar and movable in another direction 50 to release the bar from such position without destroying the adjustment.

2. In a wood-working machine, a cutter head, a bar-after-cut, an eccentric for holding the bar in working position, means for turning the eccentric to release the bar from such position, and means for locking the eccentric with the bar in working position.

3. In a wood-working machine, a cutter head, a bar-after-cut, an eccentric for holding the bar in working position, means for turning the eccentric to adjust such position, and means for yieldingly resisting turning movement of the eccentric, whereby to prevent the bar from moving inadvertently.

4. In a wood-working machine, a cutter

head, a bar-after-cut, and a rotatable and pivoted control handle which when turned will adjust the working position of the bar and when swung will release the bar from such position without destroying the adjustment. 70

5. In a wood-working machine, a top head yoke, a top head journaled in the yoke, upwardly and rearwardly inclined guides in the yoke behind the top head, a bar-after-cut 75 supported in the guides, an eccentric for holding the bar in working position, and means for turning the eccentric to move the bar in the guides.

6. In a wood-working machine, a top head yoke, a top head journaled in the yoke, a bar-after-cut supported by the yoke, an eccentric for holding the bar in working position, means for turning the eccentric slowly to adjust the working position of the bar, 80 and means for turning the eccentric rapidly to release the bar from working position.

7. In a wood-working machine, a cutter head, a bar-after-cut, an eccentric shaft for holding the bar in working position, a pinion on the shaft, a worm in mesh with the pinion, and a handle for turning the worm to rotate the pinion. 90

8. In a wood-working machine, a cutter head, a bar-after-cut, an eccentric shaft for holding the bar in working position, a pinion on the shaft, a bracket pivoted concentrically with the pinion, a worm journaled in the bracket in mesh with the pinion, and means for either rotating or swinging the 100 worm whereby to turn the eccentric shaft either slowly or rapidly.

9. In a wood-working machine, a cutter head, a bar-after-cut, an eccentric shaft for holding the bar in working position, a pinion on the shaft, a bracket pivoted concentrically with the pinion, a worm journaled in the bracket in mesh with the pinion, 105 means for either rotating or swinging the worm whereby to turn the eccentric shaft 110 either slowly or rapidly, and means for preventing the worm from rotating inadvertently.

10. In a wood-working machine, a cutter head, a bar-after-cut, an eccentric shaft for holding the bar in working position, a pinion on the shaft, a bracket pivoted concentrically with the pinion, a worm journaled in the bracket in mesh with the pinion, 115 means for either rotating or swinging the worm whereby to turn the eccentric shaft 120 either slowly or rapidly, means for preventing the worm from rotating inadvertently, and means for preventing it from swinging inadvertently.

11. In a wood-working machine, a cutter head, a bar-after-cut, an eccentric for holding the bar in working position, resiliently yieldable means pressing the bar against the eccentric, and means for turning the 130

eccentric to vary the working position of the bar.

12. In a wood-working machine, a cutter head, a bar-after-cut, a face plate on the bottom of the bar having both front and rear edges shaped for association with the cutter head, and means for permitting the plate to be reversed in position on the bar to bring the rear edge of the plate into the position formerly occupied by the front edge whereby to permit use of the rear edge upon the front edge becoming worn.

13. In a wood-working machine, a top head yoke, a top head journaled in the yoke, upwardly and rearwardly inclined guides 15 in the yoke behind the top head, a bar-after-cut supported in the guides, means for holding the bar in the guides in working position, and means for moving the bar lengthwise of the guides to or from working position.

In testimony whereof I have hereunto subscribed my name.

WALLACE D. JOHNSON.
